[57] CLAIM

The ornamental design for electronic desk top calculator, substantially as shown and described.

DESCRIPTION

FIG. 1 is a perspective view of an electronic desk top calculator showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right elevational side view thereof;

FIG. 7 is a left side elevational view thereof; and

FIG. 8 is a perspective view of an electronic desk top calculator showing a second embodiment of my new design;

FIG. 9 is a perspective view of an electronic desk top calculator showing a third embodiment of my new design;

FIG. 10 is a perspective view of an electronic desk top calculator showing a fourth embodiment of my new design; and

FIG. 11 is a perspective view of an electronic desk top calculator showing a fifth embodiment of my new design.

The embodiment of FIGS. 8-11 have similar bottom plan views to that of the first embodiment, as shown in FIG. 3.
